INVENTOR
STEPHEN PAUL,

BY *Brink & Dickey*
ATTORNEYS

UNITED STATES PATENT OFFICE.

STEPHEN PAUL, OF LANSING, MICHIGAN.

ADJUSTABLE GUIDE FOR HAMMERS.

1,405,799.

Specification of Letters Patent.

Patented Feb. 7, 1922.

Application filed October 4, 1920. Serial No. 414,412.

To all whom it may concern:

Be it known that I, STEPHEN PAUL, a citizen of the United States of America, residing at Lansing, in the county of Ingham 5 and State of Michigan, have invented certain new and useful Improvements in Adjustable Guides for Hammers, of which the following is a specification, reference being had therein to the accompanying drawings.

10 This invention has reference to punch presses, hydraulic hammers or any other structure which has guides for a reciprocable member and wherein the guides are held against accidental displacement and adapted to be adjusted from time to time to compensate for wear.

My invention aims to provide positive and reliable means, in a manner as herein-after set forth, for adjusting and holding 20 the ends of opposed guides, and the adjusting means is disposed so that easy access is had thereto for safely moving the guides without dismantling a large hydraulic or steam forging hammer or the like.

25 The construction entering into my invention will be hereinafter described and then claimed, and reference will now be had to the drawing, wherein—

Figure 1 is a side elevation of a portion 30 of a hydraulic or steam forging hammer provided with guide adjusting means in accordance with this invention;

Fig. 2 is an enlarged vertical sectional view of one of the frames of the machine;

35 Fig. 3 is a horizontal sectional view of the same, and

Fig. 4 is a perspective view of a detached adjusting member.

For the purposes of showing the guide adjusting means, it is thought only necessary 40 to show a portion of a machine having frames 1 between which reciprocates a head or member 2. The confronting faces of the frames 1 have longitudinal recesses 3 for guides 4 and the upper and lower ends of the guides are beveled inwardly from the inner faces thereof to the outer faces. The beveled end faces of the guides are designated 5 and said end faces have grooves 6 45 to receive the tongues 7 of adjusting members 8. The adjusting members 8 are somewhat in the form of wedges having beveled walls 9 and flat walls 10, the flat walls 10 engaging the flat end walls of the recesses 3, 50 as best shown in Fig. 2.

The adjusting members 8 have integral

rods or bolts 11 extending through openings 12 in each of the frames 1 and the inner ends of the openings 12 are enlarged, as at 13, to provide clearance for the adjusting 60 members. On the outer ends of the rods or bolts may be mounted nuts 14 with suitable locking devices for preventing accidental rotation of the nuts.

Each frame has transverse openings 15 communicating with the recess 3 and in the inner walls of said recess, at the openings 15, are countersunk wear plates 16 against which bear tapered members 17 extending through openings 18 provided therefor in 70 each of the guides 4, the said openings 18 aligning with the openings 15. The tapered members 18 have screw threaded shanks 19 for nuts 20 which bear against the sides of the frame 1 and permit of the tapered members 17 being shifted in either direction to distend the guides 4, thus permitting of said guides being properly adjusted for a reciprocal movement of the head or member 2. After the guides 4 are adjusted by 80 the tapered members 17 the adjusting members 8 may be tightened to positively clamp the guides against the members 17 and between the end walls of the recess 3.

It is thought that the utility of my invention will be apparent without further description, and I reserve the right to make such structural changes as fall within the scope of the appended claims.

What I claim is:—

1. In a forging machine, a frame having a recess and openings communicating with the ends of said recess, a guide in said recess and having beveled ends, and adjusting members in the ends of said recess clamping the beveled ends of said guide in said recess and operable through the openings of said frame.

2. A guide for a forging machine, as characterized in claim 1, wherein said adjusting members have flat walls engaging end walls of said recess, and tongues extending into the beveled ends of said guide.

3. In a forging machine, a frame having a recess, and sets of openings communicating with said recess, a guide in the frame recess, adjusting members between the ends of said guide and the ends of said recess, rods carried by said adjusting members and extending through one set of frame openings, nuts on said rods against said frame, and adapted to be adjusted to clamp said

adjusting members against said guide, and means extending through said guide and the other set of frame openings for shifting said guide when said adjusting members are loose.

4. A guide for a forging machine, as characterized in claim 3, wherein said adjusting members are adapted to retract said

guide and said means extend said guide relative to said frame.

In testimony whereof I affix my signature in presence of two witnesses.

STEPHEN PAUL.
